[57] CLAIM

The ornamental design for a control and measuring instruments for conditioning and refrigerating units and components for control and measuring instruments of this kind, as shown.

DESCRIPTION

FIG. 1 is a perspective view of the base instrument container comprising a front piece embodying a visor and a first small closing bottom.

FIG. 2 is a front view of the container of FIG. 1;

FIG. 3 is a rear view of the container of FIG. 1;

FIG. 4 is a top view of the container of FIG. 1;

FIG. 5 is a bottom view of the container of FIG. 1;

FIG. 6 is a first side view of the container of FIG. 1;

FIG. 7 is a second side view of the container of FIG. 1;

FIG. 8 is a perspective view of the medium instrument container comprising a front piece embodying a visor and second small closing bottom;

FIG. 9 is a front view of the container of FIG. 8;

FIG. 10 is a rear view of the container of FIG. 8;

FIG. 11 is a top view of the container of FIG. 8;

FIG. 12 is a bottom view of the container of FIG. 8;

FIG. 13 is a first side view of the container of FIG. 8;

FIG. 14 is a second side view of the container of FIG. 8;

FIG. 15 is a perspective view of the large container comprising a front piece embodying a visor, and extensin module and a large closing bottom;

FIG. 16 is a front view of the container of FIG. 15;

FIG. 17 is a rear view of the container of FIG. 15;

FIG. 18 is a top view of the container of FIG. 15;

FIG. 19 is a bottom view of the container of FIG. 15;

FIG. 20 is a first side view of the container of FIG. 15;

FIG. 21 is a second side view of the container of FIG. 15;

FIG. 22 is a perspective view of a front piece embodying the visor;

FIG. 23 is a front view of the front piece of FIG. 22;

FIG. 24 is a rear view of the front piece of FIG. 22;

FIG. 25 is a top view of the front piece of FIG. 22;

FIG. 26 is a bottom view of the front piece of FIG. 22;

FIG. 27 is a first side view of the front piece of FIG. 22; and,

FIG. 28 is a second side view of the front piece of FIG. 22.
